SOLENOID CONSTRUCTION
Hardin Y. Fisher, Hillside, Ill., assignor to
Albert F. Dormeyer, Chicago, Ill.
Filed June 12, 1959, Ser. No. 820,045
4 Claims. (Cl. 317—191)

This invention relates in general to solenoids, and more particularly to improvements in alternating current solenoids, to enhance their life. Still more particularly, this invention relates to improvements in plunger and plunger slide structure construction.

The present invention deals with improvements in the solenoid generally known in the industry as a "T-bar" plunger type solenoid, wherein the solenoid includes an elongated stem and a transversely extending bar at one end of the stem for use in a substantially C-shaped frame. This bar may be defined as a cross bar or seating bar. More particularly, the improvements are applicable to the external reluctance solenoid disclosed in applicant's copending application Serial No. 795,261, filed February 24, 1959, although it will be appreciated that the present invention may be utilized in other types of solenoids.

In a solenoid of the type above mentioned, the plunger is slidably guided in a pair of spaced non-permeable slides mounted within the frame and the hollow center of the coil. These slides are provided with rails for containing movement of the plunger stem. When the plunger is in the extended or protracted position, wear is caused on the outer ends of the rail still engaging the plunger to the extent that subsequent failure of the solenoid is caused by "freezing" of the plunger. At the under side of the plunger cross bar, an external reluctance bar is provided having a dimension of less width or of less length than the cross bar. Because of this external reluctance bar, the slide rails must terminate at a point slightly inward from the external reluctance bar in order to prevent interference in seating of the plunger.

The present invention consists of providing slots or notches in the external reluctance bar to accommodate the outer free ends of the slide rails, wherein the slide rails may be made longer and thereby provide greater support to the plunger in its extended position.

Accordingly, it is an object of this invention to provide an improved solenoid having a plunger and plunger slide structure construction which will enhance the life of the solenoid.

A further object of this invention resides in the provision of extending the life of a solenoid without increasing the cost of making the solenoid.

A still further object of this invention is in the provision of a plunger for a solenoid having an elongated stem with a cross bar at one end and inwardly extending projections defining slots with a stem for freely receiving the outer ends of the slide rails of the slide structure.

Other objects, features, and advantages of the invention will be apparent from the following detailed disclosure, taken in conjunction with the accompanying sheets of drawings, wherein like reference numerals refer to like parts, in which:

FIG. 1 is a perspective view of a solenoid embodying the present invention;

2

FIG. 2 is an enlarged perspective view of the plunger and slides removed from the solenoid frame and constructed in accordance with the present invention;

FIG. 3 is a view taken through the solenoid coil of FIG. 1 and showing the plunger slide rails as extending into the notches provided in the plunger, with some parts in section and broken away for purposes of clarity;

FIG. 4 is an enlarged, fragmentary and partially sectional view of the plunger and guide structure of the prior art, wherein the plunger is shown in seated or contracted position relative to the plunger slides;

FIG. 5 is a view similar to FIG. 4, but illustrating the present invention, and showing the difference in length of the plunger slide rails;

FIG. 6 is a view of a plunger similar to that of FIG. 4 and of the prior art and illustrating the plunger in extended or protracted position; and

FIG. 7 is a view similar to FIG. 6 showing the plunger in extended or protracted position, but of the present invention and illustrating in comparison the greater support provided for the plunger in extended position by the longer rails.

To illustrate the invention, the drawings show the solenoid of the present invention as including generally a coil 10 having a plurality of turns carried on an insulating spool or bobbin, and a pair of terminal lugs 11 for connection to an electrical source. A generally C-shaped laminated, permeable frame 12 embraces the coil 10, and has an opening at one end for receiving a pair of spaced non-permeable slides 13 and a generally T-shaped plunger 14.

The frame 12 is constructed in the usual manner by securing together a plurality of identically formed laminae 15. The stack of laminae is covered on opposite sides by a specially formed lamina 16, having spaced apart flanges 17 and 18 struck out therefrom for providing support and positioning of the coil 10. The flanges 17 and 18 are cut away or notched at their inner edges 19 to provide clearance for receiving the identical but oppositely facing plunger slides 13.

As noted particularly in FIG. 3, the C-shaped frame 12 includes parallel spaced legs 20 and 21 straddling the coil 10, and being connected together at adjacent ends by the bight 22 of the frame. At the other end of the legs 20 and 21, inwardly extending projections 23 and 24, respectively, are provided which have substantially the same cross section as the legs of the frame. Narrow projections 25 and 26 extend inwardly from the projections 23 and 24, respectively, and define therebetween an air gap or opening through which the plunger stem is received.

The plunger 14 includes generally a plurality of identically formed laminae secured together and defining an elongated stem 27, a transversely extending seating bar or cross bar 28 arranged at one end of the stem, and an external reluctance bar 29 secured to the under side of the cross bar 28.

The very free ends of the projections 25 and 26 of the frame are arranged in close proximity to the adjacent sides of the plunger stem 27, as seen in FIG. 3. The projections 25 and 26 define with the inner end faces 30 and 31 of the projections 23 and 24 a reluctance gap between the faces 30 and 31 externally of the frame opening. The plunger, as well as the frame, is constructed of a magnetically permeable material.

The plunger 14 is constructed of a plurality of identically formed laminae 32 having pull bars 33 arranged over the outer laminae, and the pull bars and laminae are held together by suitable fastening members such as rivets 34. The seating bar 28 of the plunger seats against the outer faces 35 of the C-frame when in closed position. The seating bar 28 includes seating surfaces or areas 36 which contact the outer faces 35 of the frame when the plunger is in seated position. The seating or cross bar 28 is generally rectangular in shape, and the external permeable bar 29 is also generally rectangular in shape and integral with the seating bar 28 and adjacent the under or inner side thereof. The permeable bar 29 is longer than the frame opening but of much less length than the seating bar 28, and sized to be freely received between the spaces 31 of the frame. It may be noted that when the plunger is seated as seen in FIG. 3, the plunger and frame are constructed so that the inner ends of the permeable bar 29 cannot contact the projections 25 and 26.

Referring now particularly to FIG. 2, it is seen that each slide includes a main body 37 having a pair of spaced plunger supporting rails 38 extending perpendicularly from opposite edges thereof and extending nearly the entire longitudinal length of the body, thereby defining a more or less channel-shaped slide. At the lower end of each slide, the plunger supporting rails 38 terminate at 39 so that the main part of the body may be arranged along the outer sides of the C-shaped frame as is seen in FIG. 3, and the terminal end 39 of the rails abuts against the inner side of the bight 22. The rails 38 extend substantially perpendicular to the body 37. A portion of the rails 38 is cut away at the upper end to provide clearance for the seating bar 28 and the permeable bar 29. The width of the rail 38 is sufficient to give adequate support to the plunger stem, and generally equal to the thickness of a pull bar 33 and two or three laminae 32. Where the supporting rails 38 are cut away at the upper end, a very narrow supporting flange 40 is formed which has a width slightly less than the width of a pull bar 33 to further give support to the plunger along opposite sides of the plunger inasmuch as the pull bar extends the full length of the plunger. Accordingly, the upper terminal edges or ends of the rails, as indicated at 41, must be slightly spaced from the plunger permeable bar 29 when the plunger is in seated position.

In forming the slides 13, a stamping and punching operation is generally utilized, wherein the slides may be stamped and punched from a piece of material to the required configuration, and with some parts punched out as waste. Thus, the portions punched away at the upper and lower ends of the slide to define the terminal ends 39 and 41 of the rails would constitute waste material.

In order to best illustrate the present invention, FIGS. 4 and 6 disclose the prior art, wherein FIG. 4 shows the plunger relative to the slide in closed or seated position, while FIG. 6 shows the plunger relative to the slide in extended or protracted position. The parts to the plunger and slide in FIGS. 4 and 6 are numbered identically to that of the present invention and already covered, but suffixed b/ the letter a.

FIGS. 5 and 7 represent the construction of the present invention and illustrate clearly the difference in structure over the prior art of FIGS. 4 and 6.

Slots or notches 42 are formed in the permeable bar 29, and open toward the lower end of the stem 27, and define projections 43 extending from the under side of the seating bar 28, as seen in FIGS. 2, 3, 5 and 7.

As seen in FIG. 5, the upper terminal ends 41 of the rails 38 are received freely within the notches or slots 42 of the plunger. It may be seen that the rails 38 of the present invention are longer than the rails 38a of the prior art as shown in FIGS. 4 to 7. Further, in comparing the extended positions of the plungers, as in

FIGS. 6 and 7, it is noted that the plunger of the present invention has a greater rail support by the longer rails than the plunger of the prior art in FIG. 6. This extension of the rails 38 enhances the overall life of the solenoid, but adds nothing to the cost of making the solenoid inasmuch as the portions of the rails normally removed from the slides of the prior art only constitute waste, and is done by a punching or similar operation. Further, the laminae 32, which make the plunger, are formed from a single stamping operation, and therefore it does not require any extra machining or labor cost.

From the foregoing, it will be appreciated that the plunger and slide construction of the present invention is such as to enhance the life of a solenoid without increasing the cost thereof.

It will be understood that modifications and variations may be effected without departing from the scope of the novel concepts of the present invention, but it is understood that this application is to be limited only by the scope of the appended claims.

The invention is hereby claimed as follows:

1. In a solenoid, a coil with a hollow center, a substantially C-shaped frame embracing said coil having a narrow opening at one end aligning with the hollow center of the coil, a plunger slide structure including a pair of spaced non-permeable slides arranged in the opening of said frame and the hollow of the coil, said slides having plunger supporting rails and a plunger, said plunger having an elongated stem reciprocable in said slides and guidably supported by said plunger supporting rails, a transversely extending bar at the outer end of said stem, and projections extending from said bar along opposite sides of the stem defining slots for freely receiving the outer free ends of said rails which are of sufficient length to extend into said slots when the plunger is in seated position.

2. In a solenoid, a coil having a hollow center, a substantially C-shaped frame embracing said coil having a narrow opening at one end aligning with the hollow center of the coil, a plunger slide structure including a pair of spaced non-permeable, channel-shaped slides arranged in the opening of the frame and the hollow of the coil, said slides having plunger supporting rails, a substantially T-shaped plunger, said plunger comprising an elongated stem reciprocable in said slides, a transversely extending bar at the outer end of the stem, and projections extending from said bar toward the free end of the stem along opposite sides of the stem defining slots for freely receiving the outer free ends of the plunger supporting rails, said rails being of sufficient length so that they extend into said slots when the plunger is in seated position.

3. In a solenoid, a coil having a hollow center, a substantially C-shaped frame embracing said coil having a narrow opening at one end aligning with the hollow center of the coil, a plunger slide structure including a pair of spaced non-permeable, channel-shaped slides arranged in the opening of the frame and the hollow of the coil, said slides having plunger supporting rails, a substantially T-shaped plunger, said plunger comprising an elongated stem reciprocable in said slides, a transversely extending bar at the outer end of the stem, and projections extending from said bar toward the free end of the stem along opposite sides of the stem defining slots for freely receiving the outer free ends of the plunger supporting rails, the supporting rails being of such a length as to extend into said slots in said plunger substantially the entire depth thereof when the plunger is in seated position.

4. In a solenoid, a coil having a hollow center, a substantially C-shaped frame embracing said coil having a narrow opening at one end aligning with the hollow center of the coil, a plunger slide structure including a pair of spaced non-permeable, channel-shaped slides arranged in the opening of the frame and the hollow of the coil,

said slides having plunger supporting rails, a substantially T-shaped plunger, said plunger comprising an elongated stem reciprocable in said slides, a transversely extending bar at the outer end of the stem, a second transversely extending bar along the side of the first mentioned bar facing the free end of the stem, said second bar having a length less than the length of said first mentioned bar, and slots extending inwardly of said second bar on opposite sides of the stem and paralleling

the longitudinal axis of said stem, said slots freely receiving the outer ends of said supporting rails which are of sufficient length to extend into said slots when the plunger is in seated position.
